GAS GUN

Gerald P. McManamna and Kurt F. J. Kirsten,
Seattle, Wash.

Application November 25, 1933, Serial No. 699,688

2 Claims. (Cl. 169—31)

This invention relates to improvements in what are known in trade as "gas guns" and which are of that character for forcibly discharging a stream, or spray of finely divided material from the device; it being the principal object of this invention to provide a device of the above character especially useful as a fire extinguishing means and comprising a container from which the fire extinguishing material is fed to the container outlet and forcibly ejected by reason of expansion of gas confined under pressure therein.

More specifically stated, the objects of this invention reside in the provision of a device of the character above stated comprising an air tight material container having a valve controlled delivery nozzle at one end, and which container is divided interiorly by a floating or movable partition, into separate compartments for the gas and material respectively and which partition, incident to opening of the nozzle valve, will be moved by pressure of gas in the other compartment to feed the material to the nozzle in accordance with its rate of ejection with the escaping gas.

Other objects of the invention reside in the details of construction of the various parts, in their combination and mode of operation as will hereafter be fully described.

In accomplishing these, and other objects of the invention, I have provided the improved details of construction, the preferred forms of which are illustrated in the accompanying drawing, wherein—

Fig. 1 is a central, longitudinal section of a gas gun embodying the present invention.

Fig. 2 is a cross section of the same as on line 2—2 in Fig. 1.

Fig. 3 is an enlarged sectional detail of a part of the imperforate floating partition.

Referring more in detail to the drawing—

1 designates what may be a cylindrical container, or bottle, of suitable material, preferably metal, capable of withstanding the internal pressure of gas to which it is subjected in use. At one end the container terminates in a spout 2 onto which a discharge nozzle 3 is threaded. Associated with the nozzle is a valve 4 for controlling the delivery of material and this valve is opened and closed by a hand lever 5. Slidably fitted in the cylinder is a partition wall 6 dividing the cylinder into opposite end compartments; the compartment at the nozzle end of the device being designated as the dust or material compartment and that at the other end being designated as the gas compartment. Under action of gas pressure at one side, the partition or piston is

adapted to be moved to advance the supply of material or dust, designated at 7, to the nozzle.

The piston, as herein shown, is provided on one face with legs 8 adapted to engage the end wall of the gas compartment to limit movement of the partition in that direction and to insure a compartment of a definite size for containing the gas under pressure. The piston, as seen in Fig. 3, has perforations 9 formed therein so as to permit the gas to slowly flow or escape through it to balance or tend to balance pressures against opposite sides of the partition.

For convenience in filling the device with gas, a nipple 10 is provided in the end wall opposite the nozzle for attachment of a hose or tube leading from the gas supply. Normally this nipple is closed by a plug or cap 11, as shown.

In filling the device the nozzle is removed and the partition wall adjusted to a position against the opposite end of the container. Then the dust compartment is filled and the nozzle replaced. Then the cylinder is charged with gas through nipple 10, and the gas held by applying the plug 11. The gas that is thus trapped under pressure permeates the material and forms a body of concentrated gas in the gas compartment.

In using the device, the nozzle valve 4 would be opened to any extent desired, and this will permit an outflow of gas which carries with it a stream, or spray of the material 7. Reduction of the gas pressure at that end of the container permits the greater pressure of gas at the opposite end to shift the piston or partition toward the nozzle end and thereby to advance the supply of material to the nozzle in accordance with the rate at which it is used. The gas escaping from the gas chamber through the perforations of the piston, then through the supply of material and finally through the nozzle carries with it the divided material. Thus the feeding of material is automatic and under direct control of the nozzle valve.

Devices of this character may be made in various sizes and proportions, and of various materials to meet various requirements, and therefore, it is not desired that the claims should be limited to the details or proportions shown, but shall be given an interpretation commensurate with the scope of the invention disclosed.

Such devices are useful for various purposes but the present design is especially useful for fire extinguishing purposes.

Having thus described my invention, what I

claim as new therein and desire to secure by Letters Patent is—

- 5 1. A device of the character described comprising a closed container having an outlet and a closure means therefor, a floating partition dividing the container into two separate compartments, respectively, for containing a concentrated supply of expandable pressure medium and a divided material and movable under pressure of the expandable medium toward the outlet to advance material in the material compartment thereto; said partition being constructed and arranged so as to establish restricted communication between said compartments so that some of 10
15 said medium will enter the material compartment to aid in expelling the material from the outlet.

2. A device of the character described comprising a closed container having an outlet and a closure means therefor, a floating partition dividing the container into two separate compartments, respectively, for containing a concentrated supply of expandable pressure medium and a divided material and movable under pressure of the expandable medium toward the outlet to advance material in the material compartment thereto; said partition having perforations there-through constructed to cause restricted leakage of pressure medium into the material compartment for escape through the outlet as a carrier for the material.
